UNITED STATES PATENT OFFICE.

CHESTER N. MORGAN, OF LOS ANGELES, CALIFORNIA.

READING REST.

Application filed December 15, 1924. Serial No. 755,851.

This invention has to do with devices for holding books and the like for bed-ridden patients or chair occupants.

It is the general object of the invention to provide a simple, effective device that can be easily adjusted to a bed or chair of any reasonable width or height and is capable of supporting a book at any desired angularity and any distance from the reader's eyes irrespective of what position said reader may occupy. The device is readily collapsed so as to occupy a minimum of space when not in use, and is preferably mounted on rollers or casters so as to be easily moved from place to place when collapsed and rolled into proper association with the bed or chair when spread to operative position.

The rack portion of the device is so constructed that the book is positively held open at any particular page and is held to the rack so it may be swung to occupy a substantially horizontal plane (when the patient is flat on his back) without danger of its becoming displaced or dropping.

Other objects and novel features of the invention will be made apparent as the following detailed description progresses. Reference will be made to the accompanying drawings, in which:

Fig. 1 is a perspective view of my device in assembled and operative position;

Fig. 2 is an enlarged, contracted section on line 2—2 of Fig. 1;

Fig. 3 is a horizontal section on line 3—3 of Fig. 2;

Fig. 4 is a detached front elevation of the book rack in expanded position, parts being broken away and shown in section to disclose underlying parts;

Fig. 5 is a detached rear elevation of the rack.

Fig. 6 is a horizontal section on line 6—6 of Fig. 5;

Fig. 7 is a vertical section on line 7—7 of Fig. 5;

Fig. 8 is a section on line 8—8 of Fig. 1, but showing a book in position on the rack.

Fig. 9 is a view similar to Fig. 5 but showing the book rack collapsed; and

Fig. 10 is a fragmentary perspective illustrating the joint between the book rack and depending supporting arm.

First referring to Figs. 1 and 2, I provide an inverted U-frame 10 adapted to straddle or bridge a bed or chair. Uprights 11 of

frame 10 are made up of telescopically arranged pipes or rods 12, 13 which are adapted to be held in adjustment by set screws 14 having handles of a size for comfortable manipulation. The uprights are forked at their lower extremities and the furcations or feet 15 thus formed are preferably provided with rollers 16.

Cross bar 17 of the U-frame is made up of telescopically arranged members 18 and 19 which are joined to uprights 12 by elbows 20. By telescoping the cross bar, uprights 12 may be spread apart or drawn together according to the size of the reader's bed or chair, and when drawn clear together for storage, the assembly occupies comparatively little space. Tubular member 19 is preferably fluted or has inwardly depressed projections 21 extending longitudinally therethrough. The sleeve 22, which is part of and extends transversely to the major axis of rack supporting arm 23, is complementarily fluted so it may be slid along tube 19 but is held against rotation thereabout. Should it be desired to vary the angularity of arm 23 with respect to the bed, sleeve 22 is slipped off the free end of tube 19, rotated to the desired angular position and then slipped back on the tube, the flutings of sleeve and tube re-engaging to prevent subsequent undesirable rotation of the arm. Of course, it lies within the scope of my invention to substitute any suitable means for detachably keying or splining sleeve 22 and tube 19 to give the above described result. The adjustment just described is necessarily somewhat coarse, as there are only a limited number of flutings and these may not register when arm 23 is in the desired angular position. However, I provide means (to be later described) for tilting book rack R with respect to arm 23 to secure a finer adjustment of book angularity.

Arm 23 is preferably of telescopic nature so its effective length may be varied to suit any particular situation. For instance, it may be made up of nested tubes 24, 25 and rod 26, there being co-acting heads 27 and flanges 27^a on the arm members for preventing separation thereof. Spring pressed latch 28 on tube 24 is adapted to engage selectively shoulders 29 and 30 of tube 25 and rod 26, respectively, slots 31 in tube 25 extending through the sleeve wall so the point of the latch may engage shoulders 30 when they are in register with said slots.

It is obvious how latch 28 holds member 24, 25, and 26 in adjustment.

The lower end of rod 26 is provided with a laterally off-set hook 32 adapted to support 5 attachment member 33 pivotally. This member may conveniently, though not necessarily, be made up of spaced angles 34, the forward flanges 35 of the angles being joined by plate 36, and angle flanges 38 being joined 10 by pivot pin 37 which is adapted to rest in the hook notch. In order to hold member 33 in adjusted angular position with respect to rod 26, I provide a lock bar 39 pivoted to member 33 and having a series of notches 15 40 adapted to be brought into selected register with headed pin 41 on rod 26.

Book rack R is made up of opposed channels 42, 43 (the grooves of the channel being face to face) joined by lazy tong devices 44 20 and 45 whereby said channels may be moved towards and away from each other without disturbing their parallelism. The central cross bar 46 is pivoted to channel 43 at 47 and is adapted to lie in either of the two 25 yokes 48^a when the rack is collapsed. When the rack is to be used, tongs 44 and 45 are extended, bar 46 is swung to a vertical position, and the channels then brought together until keeper strap 48 on channel 42 slips over 30 the end of the bar to maintain it in vertical position. Bar 46 is provided with socket member 49, of any usual construction, adapted to be slipped over attachment member 33 on rod 26, shoulder 50 engaging the 35 top of the attachment member to prevent downward separative movement of bar 46 with respect to bar 26. With the rack thus detachably mounted on rod 26, it may be raised, lowered, tilted or swung about cross bar 17 by the various adjustments previously 40 described.

When a book B is to be supported by rack R, the book is opened at the desired pages, 45 spread apart, and the lower edges dropped into the groove of channel 43. Channel 42 is lifted until it clears the top of the book, the book is swung back until its covers engage tongs 44, 45 with the back of the binding resting against bar 46, and channel 42 50 is then depressed until its flanges embrace the upper edge of the book. Yoke 48, of course, slides over bar 46 during vertical movement of channel 42 with respect to channel 43, and hence the connection between 55 said bar and channel 42 may be termed a "slip-joint connection." This channel engagement with the top and bottom of the book is normally adequate to hold the book spread open at the desired place and serves 60 to retain the book in position on the rack even though the rack be swung into a substantially horizontal plane. However, to insure that the leaves of the book lie flat I may provide spring clips or clasps 51 on 65 channels 42 and 43. Preferably, these clasps

are pivoted to the channels so they may be swung to the position of Fig. 4 when they are not needed for holding the book pages flat. The clasps are shown in operative position in Fig. 8.

It will be seen that the above mentioned "slip-joint connection" is a disengageable one and that the channel members are movable apart a sufficient distance to cause disengagement of said connection and thereby allow 75 bar 46 to be swung pivotally into substantial parallelism with the channel members.

I also find it desirable in some instances to provide clasps or clips for engaging the binding of the book where it is exposed by 80 the spread leaves. For this purpose I may provide spring clips 52 pivoted to the channels at 53 and adapted to extend vertically in horizontal opposition to bar 46 or to be swung between the channel flanges when not 85 in use or when it is desired to collapse the rack.

It is believed a full understanding of the invention will be had from the foregoing, but it will be understood various changes in 90 design, structure and arrangement lie within the scope of my broader claims, and therefore, I do not wish to be limited to the illustrated and described embodiment of the invention except for such limitations as a fair 95 interpretation of the appended claims may import.

Having described a preferred form of my invention, I claim:

1. In an adjustable reading rack, an inverted U-frame, a rack pendant supporting arm extending radially from and slidable along the cross bar of the frame, means adapted to hold the arm in selected angular relation with respect to the bar, a book rack 100 pivoted to the arm for angular movement through a vertical plane, and releasable locking means for securing the rack in selected angular position with relation to the arm.

2. In a rack for adjustable rests, a pair of opposed, elongated horizontal members movable towards and away from each other, a pair of lazy tongs connecting said members near their ends, a bar extending from member to member between said lazy tongs, a pivotal connection between the bar and one of the members, and a disengageable slip-joint connection between the bar and the other member, said members being movable away from each other to an extent allowing disengagement of said slip-joint connection whereby the bar is then pivotally movable towards said one member.

3. In an adjustable reading rack, an inverted U-frame, the cross-bar of the frame being longitudinally telescopic and having a portion with longitudinally extending flutes, and a rack supporting arm including a sleeve adapted to slide longitudinally over the cross-bar and having internal flutes comple- 130

mentary to the flutes of the cross-bar, the inter-fitting of the flutes on bar and sleeve being adapted to hold said bar and sleeve against relative rotation, and the sleeve being 5 slidable along and off the end of the fluted portion of the bar, whereby the sleeve thereafter may be moved angularly with respect to the bar and then slid back to re-engage the flutes of the bar and sleeve and thereby being held in its new position of 10 angular adjustment.

4. In a rack for adjustable rests, a pair of opposed, elongated horizontal members movable towards and away from each other, 15 a pair of lazy tongs connecting said members near their ends, a bar extending from member to member between said lazy tongs, a pivotal connection between the bar and one of said members, whereby said bar is movable 20 pivotally from its position of such extension into a position substantially paralleling said members, and a spring clip pivotally secured to one of the members and swingable from a position substantially paralleling said members to a position substantially 25 paralleling and in horizontal opposition to said bar when said bar extends from member to member.

5. In an article of the character described,

a supporting bar having a portion with longitudinally extending flutes, and a rack supporting arm including a sleeve adapted to slide longitudinally over the cross-bar and having internal flutes complementary to the flutes of the cross-bar, the inter-fitting of 30 the flutes on bar and sleeve being adapted to hold said bar and sleeve against relative rotation, and the sleeve being slidable along and off the end of the fluted portion of the bar, whereby the sleeve thereafter may be 35 moved angularly with respect to the bar and then slid back to re-engage the flutes of the bar and sleeve and thereby being held in its new position of angular adjustment.

6. In a device of the character described, 40 a horizontal supporting bar, a pendant rack supporting arm extending radially from said bar, means adapted to hold the arm in selected angular relation with respect to the bar, a book rack pivoted to the arm for angular movement through a vertical plane, and releasable locking means for securing the rack in selected angular position with relation to the arm.

In witness that I claim the foregoing I 45 have hereunto subscribed my name this 12th day of November, 1924.

CHESTER N. MORGAN.

CERTIFICATE OF CORRECTION.

Patent No. 1,719,190.

Granted July 2, 1929, to

CHESTER N. MORGAN.

It is hereby certified that error appears in the printed specification of the above numbered patent requiring correction as follows: Page 2, line 101, claim 1, strike out the word "pendant" and insert same before "rack" same line and claim; and that the said Letters Patent should be read with this correction therein that the same may conform to the record of the case in the Patent Office.

Signed and sealed this 6th day of August, A. D. 1929.

(Seal)

M. J. Moore,
Acting Commissioner of Patents.
